G. GODDU AND F. L. MACKENZIE,
NAIL FEEDING MECHANISM,
APPLICATION FILED MAY 2, 1919.

1,408,451.

Patented Mar. 7, 1922.

UNITED STATES PATENT OFFICE.

GEORGE GODDU, OF WINCHESTER, AND FRED L. MACKENZIE, OF BEVERLY, MASSACHUSETTS, ASSIGNORS TO UNITED SHOE MACHINERY CORPORATION, OF PATERSON, NEW JERSEY, A CORPORATION OF NEW JERSEY.

NAIL-FEEDING MECHANISM.

1,408,451.

Specification of Letters Patent.

Patented Mar. 7, 1922.

Application filed May 2, 1919. Serial No. 294,281.

To all whom it may concern:

Be it known that we, GEORGE GODDU and FRED L. MACKENZIE, citizens of the United States, residing at Winchester, in the county 5 of Middlesex, and Beverly, in the county of Essex, respectively, and State of Massachusetts, have invented certain Improvements in Nail-Feeding Mechanism, of which the following description, in connection with the

10 accompanying drawings, is a specification, like reference characters on the drawings indicating like parts in the several figures:

This invention pertains to nail feeding mechanism of the type usually employed in 15 machines for inserting loose nails. Such machines commonly comprise a fastening receiving member having a passage in which a driver reciprocates and which is open at one side to receive the nails from a raceway 20 having a slot in which the nails are supported by their heads. The raceway is usually formed at its delivery end with lugs between which is interposed a separator by which the nails are delivered one by one 25 from the raceway to the receiving member. In order that the nails may be fed efficiently to the receiving member, it is necessary that the slot of the raceway be accurately aligned with the passage of said member and that 30 the raceway be correctly positioned relatively to the separator, and it is desirable that these ends shall be attained without the exercise of excessive care in machining the raceway. It is also customary to provide a cover plate 35 over the slot of the raceway to preclude the escape of the nails from the raceway.

An object of the invention is to provide an improved raceway construction and to provide improved supporting and adjusting 40 means for such raceways and their cover plates. To this end, an important feature of the invention consists in the provision of connections between the raceway and its supporting means spaced longitudinally of the 45 raceway and constructed and arranged to permit vertical adjustment of the raceway relatively to its supporting means. As shown, independent eccentric means are provided for adjusting the raceway at different 50 points, and, in the illustrated construction also, such means comprise eccentric sleeves constituting parts of the connections between the raceway and its supporting means.

In accordance with another feature of the

invention, the cover plate is supported for 55 vertical adjustment so that it may be disposed in proper relation to the raceway when the raceway is raised or lowered. This arrangement possesses the further advantage that adjustment of the cover plate does not 60 change the relation of the lower end of the cover plate to the path of movement of the driver.

Another important feature of the invention resides in mounting the cover plate for 65 pivotal movement so that it may be adjusted conformably with the raceway when one of the ends of the raceway is raised or lowered with relation to the other.

A still further feature of the invention 70 consists in the provision of means for adjusting the supporting means for the raceway and the cover plate so that such parts may be made to occupy any desired position 75 relatively to the other elements of the machine without changing their positions with relation to each other.

Heretofore, both the upper and lower lugs on the delivery end of the raceway have been formed integrally with the raceway. 80 The upper lugs which conduct the nails from the raceway to the fastening receiving member are difficult to machine inasmuch as they must be so formed as to possess the requisite strength and at the same time to permit 85 the heads of the nails to approach as closely as possible to the upper part of the separator so that the separator will not turn the nails about their heads and will thereby be enabled to introduce the nails properly 90 into the passage of the fastening receiving member. Moreover, they are sometimes broken in use, in which case the entire raceway is rendered useless. In order to obviate 95 the above objections, we provide detachable members on either the fastening receiving member or the raceway for conducting the nails from the raceway to the fastening receiving member. For the purposes of this invention, such members are preferably provided on the raceway and, in the present instance of the invention, they are formed 100 as plates extending beyond the delivery end of the raceway.

Although the invention will be described 105 herein as embodied in a machine for inserting loose nails, it is recognized that it is not limited in its application to such ma-

chines, but may be used in machines of other kinds including those for performing operations of a different character on loose nails. Accordingly, it is intended that the scope 5 of the invention shall not be limited except as required by the claims.

Still other objects and features of the invention will appear as the description proceeds and will be pointed out in the appended 10 claims.

In the drawing,

Fig. 1 is a view in front elevation of the head of a fastening inserting machine embodying the invention;

15 Fig. 2 is a view in perspective of the raceway supporting and adjusting mechanism;

Fig. 3 is a view in transverse cross-section through substantially the middle of the raceway supporting and adjusting mechanism;

20 Fig. 4 is an exploded view of the raceway and the cover plate therefor;

Fig. 5 shows the removable tips at the delivery end of the raceway; and

25 Fig. 6 is a view of the delivery end of the raceway with one of the tips removed.

The invention is herein shown, by way of example, as embodied in a nailing machine of the type comprising a head 2 having slidably mounted therein a driver bar 4 to which 30 is clamped a driver 6 reciprocable vertically in a passage of the driver guide 8 secured fixedly to the frame 2. The driver guide 8 constitutes a fastening receiving member and the passage of the guide is open at one 35 side to permit the nails to be driven to be successively introduced therein, from whence they drop into the nail passage of a throat 10. The throat 10 is withdrawn rearwardly of the machine intermediate between consecutive nail inserting operations to permit 40 the work to be fed by an awl 12 carried by an awl bar 14 vertically slidable in a groove formed in a slide 15 mounted in a bracket 16 carried by the frame 2. The slide 15 is 45 reciprocated in a direction to feed the work by a lever 18 operated by a cam 20 on the main shaft 21 of the machine. A support 22 upholds the work against a presser plate 24 while the nails are being inserted in it.

50 The nails are supplied to the driver guide 8 and throat 10 from a hopper 26 journaled in a bracket 27 extending laterally from the frame 2 of the machine and operated by gearing 28. The hopper 26 delivers the nails to a raceway 29 slotted to receive them and having lugs or tips 30 and 32 at its delivery end designed to abut against the surface of the driver guide 8 at each side of the slot formed in said surface by the driver passage.

55 The slot of the raceway 29 is adapted to align with the passage in the driver guide 8 and is overlain by a cover plate 33 which prevents the escape of the nails from the raceway. The nails are moved one by one from 60 the raceway into the passage of the guide

8 by a separator 34 comprising parts operable between the end of the raceway and the driver guide above and below the lugs 30.

To the end that the nails may be conducted 70 reliably and efficiently from the raceway 29 to the driver guide 8, it is necessary that the slot of the raceway shall be accurately aligned with the passage of the driver guide and that the tips of the raceway shall abut 75 properly against the contiguous surface of the guide and shall, moreover, be correctly disposed relatively to the separator 34. In order that the raceway 29 may be properly positioned at its delivery end and also with 80 relation to the hopper 26 without the necessity for the exercise of excessive care in the machining of the raceway, improved means is provided for adjusting the raceway. In the illustrated construction, the raceway 29 is supported by upper and lower blocks 36 and 38 respectively having grooves in which are received the dove-tailed lugs 40 and 42 on the raceway. The blocks 36 and 38 are split to permit endwise adjustment of the raceway relatively thereto and are adapted 85 to be clamped against the members 40 and 42 on the raceway by bolts 44 to secure the raceway in adjusted position. It sometimes happens in the use of loose nailing machines of the type herein illustrated that the nails 90 jam at the end of the raceway making it impossible for the separator to pass between them and precluding the proper delivery of the nails to the passage of the driver guide 8. In such a case, it may be necessary to withdraw the raceway from the driver guide to allow the jammed nails to be removed. With 100 this construction, the withdrawal of the raceway may be readily effected after loosening the bolts 44.

The blocks 36 and 38 have reduced studs 46 extending laterally therefrom and received in the outturned ends of a bracket 48. In order to provide for adjustment of the blocks 36 and 38 and consequently of the raceway 29 relatively to the bracket 48, the studs 46 of the blocks are enclosed by eccentric sleeves 50 rotatably mounted in the bracket 48 and preferably so formed as to facilitate their rotation by the operator. As 110 shown, they are provided with spaced peripheral openings 52 adapted to receive a suitable tool and are fitted tightly into the bracket 48 in order that they may be retained in any position to which they may be moved. The raceway 29 may be adjusted bodily upwardly or downwardly or endwise by means of the eccentric sleeves 50 and the degree of inclination of the raceway may be varied by raising or lowering one end of the raceway 115 without adjustment of the other or by adjusting the ends of the raceway in opposite directions or to unequal degrees in the same direction.

To the end that the slot of the raceway 120

may be accurately aligned with the passage of the driver guide 8, means is provided for shifting the shank 46 of the lower block 38 endwise in the eccentric sleeve 52. In the 5 illustrated exemplification of the invention, such means comprises a screw 54 threaded into an ear 56 upstanding from the bracket 48 and formed with an enlarged collar or flange 58 fitting between parallel lugs 60 on the block 38. Manifestly, rotation of the 10 screw 54 will shift the delivery end of the raceway relatively to the slot of the driver guide.

The cover plate 33 at its lower end is 15 preferably disposed close to the path of movement of the driver so as to prevent upward movement of the nails at the delivery end of the raceway. Manifestly, also, it is necessary that the cover plate be adjusted 20 accordingly when the raceway is raised or lowered. In order that the cover plate may be located as close as practicable to the path of movement of the driver without danger of its being interposed in the path of movement of the driver when it is adjusted, the 25 plate is arranged for vertical adjustment parallel to the path of movement of the driver. To this end the cover plate is formed with a groove 61 arranged obliquely of the plate at an angle such as to cause the groove to be disposed substantially vertically when the cover plate is in position over the raceway. The cover plate 33 is preferably carried by the bracket 48, which, in the present instance of the invention, is provided 30 with an upwardly extending portion 62 in which is mounted the reduced end of a stud 64, the head of which has a rib 66 normally vertically disposed and fitting into the groove 61 of the cover plate. The plate 33 is preferably secured to the stud 64 by a screw or the like 70 passing through a slot in the cover plate 33 and threaded into the stud 64. The slot of the cover plate is elongated longitudinally of the groove 61 thereby 40 permitting it to be moved bodily upwardly or downwardly to conform with bodily upward or downward adjustments of the raceway 29. In order that the cover plate may be properly disposed relatively to the raceway after the inclination of the raceway has been varied by an upward or downward adjustment of the ends of the raceway relatively to each other, the stud 64 is mounted 45 for rotation in the upwardly extending portion 62 of the bracket 48, and is adapted to be secured in any position of angular adjustment to which it may be moved by a screw or the like 72 passing through ears formed on the bracket 48.

In the illustrated construction, the bracket 48 is fulcrumed on a pin 74, see Fig. 3, depending from a collar 76 and disposed substantially parallel to the vertical plane of the raceway. Slots 78 are formed in the

bracket 48 on each side of the pin 74 and concentric thereto, and the bracket is secured in adjusted position on the collar 76 by screws 80 passing through the slots 78. The collar 76 is in turn carried rotatably by a 70 stud 82 projecting laterally from a plate 84 secured by bolts 86 in a groove formed in the bracket 27. The bolts 86 pass through vertically elongated slots in the plate 84. With this construction, the raceway may, if 75 desired, be bodily adjusted upwardly or downwardly by a single operation and without changing the relation between the raceway and the cover plate 33 by raising or lowering the plate 84 on the bracket 27. 80 Moreover, the raceway and cover plate may be moved together lengthwise of the stud 82 or may be turned about the stud 82 as a fulcrum being maintained in adjusted position on said stud by the bolt 88. Joint movement of the raceway and cover plate transversely of the vertical plane of the raceway may be effected about the pin 74 as a center. It is manifest from the foregoing, that the raceway and cover plate may be adjusted as 90 circumstances attendant upon the operation of the machine or the size or other characteristics of the nails may require.

It is recognized that many of the advantages of the invention may be obtained without provision for all of the adjustments herein provided for. For example, such adjustment as could be effected if the bracket 48 were directly and rigidly connected to the bracket 27 would probably be sufficient under 100 some conditions of operation of the machine.

Heretofore, raceways have been constructed with both the upper and lower tips formed integrally with the raceway. Such construction of the raceway has proved satisfactory in the main, but it sometimes happens that one or both of the upper tips is broken, for example, by reason of the jamming of the nails at the delivery end of the raceway in such a manner that the force of the driver is transmitted to the tips. Moreover, the tips, particularly the one on the outer side of the slot of the raceway toward which the nails are urged when engaged by the separator may become so worn as to be unfit for further use. In either case, the entire raceway is rendered useless. Furthermore, it is necessary in the construction of the raceway that the upper tips be machined with considerable care thus adding to the trouble and expense of manufacture. In order to avoid these disadvantages without sacrificing any of the virtues of the former construction, we make the upper tips 32 115 separate from the raceway. As shown, the raceway is recessed on each side to form shoulders 90, and the tips 32 are formed integrally with plates 92 adapted to be secured to the shoulders 90 by screws or the like 94. 120 125

- The plates 92 project beyond the end of the raceway and are turned inwardly at 96 across the ends of the walls of the raceway, such inturned portions having their upper surfaces disposed in alignment with the upper surfaces of the walls of the raceway. The plates 92 can be manufactured cheaply and, if they are broken or worn, can be readily replaced.
- Having fully described our invention what we claim as new and desire to secure by Letters Patent of the United States is:
1. In a machine of the class described, a raceway for conducting nails supported from their heads in pendant relation to the raceway throughout the entire length of the raceway, means for rigidly supporting the raceway, and eccentric means for adjusting the raceway relatively to its supporting means.
  2. In a machine of the class described, a raceway for conducting nails supported from their heads in pendant relation to the raceway throughout the entire length of the raceway, means for supporting the raceway, and eccentric sleeves journaled in said supporting means for adjusting the raceway.
  3. In a machine of the class described, a raceway for conducting nails supported from their heads in pendant relation to the raceway throughout the entire length of the raceway, supporting members therefor relatively to which the raceway is longitudinally adjustable, and eccentric means for adjusting said supporting members.
  4. In a machine of the class described, a raceway for conducting nails supported from their heads in pendant relation to the raceway throughout the entire length of the raceway, supporting members therefor relatively to which the raceway is longitudinally adjustable and formed with shanks extending transversely of the raceway, and rotatably mounted eccentric sleeves adapted to receive said shanks.
  5. In a machine of the class described, a rigid raceway for conducting headed fastenings supported from their heads in pendant relation to the raceway throughout the entire length of the raceway, means for supporting the raceway, and connections between the raceway and the supporting means spaced longitudinally of the raceway and constructed and arranged to permit vertical adjustment of the raceway relatively to the supporting means.
  6. In a machine of the class described, a rigid inclined raceway for conducting nails supported from their heads in pendant relation to the raceway throughout the entire length of the raceway, and means for adjusting one of the ends of the raceway independently of the other to vary the inclination of the raceway.
  7. In a machine of the class described, a rigid raceway, means for supporting the

raceway, and connections between the raceway and the supporting means spaced longitudinally of the raceway and comprising means for effecting both vertical and longitudinal adjustment of the raceway. 70

8. In a machine of the class described, a rigid raceway for conducting headed fastenings supported from their head in pendant relation to the raceway throughout the entire length of the raceway, means for supporting the raceway, and connections between the raceway and the supporting means spaced longitudinally of the raceway, one of said connections comprising means for adjusting the raceway relatively to the supporting means. 75

9. In a machine of the class described, a rigid raceway, supporting members for the raceway spaced longitudinally of the raceway and relatively to which the raceway is longitudinally movable, and means for adjusting one of said supporting members. 85

10. In a machine of the class described, a rigid raceway, supporting members for the raceway spaced longitudinally of the raceway and relatively to which the raceway is longitudinally movable, and means for adjusting one of said supporting members in either of two directions. 90

11. In a machine of the class described, a raceway, supporting members for the raceway spaced longitudinally of the raceway, eccentric means for adjusting one of said supporting members parallel to the plane of the raceway, and means for adjusting said member in a direction transverse to the plane of the raceway. 95

12. In a machine of the class described, a raceway, supporting means for the raceway, and connections between the supporting means and the raceway at spaced points of the raceway comprising means for adjusting the upper and lower ends of the raceway in opposite directions. 105

13. In a machine of the class described, a raceway, supporting means for the raceway, and connections between the supporting means and the raceway at spaced points of the raceway comprising means operable to adjust the ends of the raceway in the same direction or in opposite directions. 110

14. In a machine of the class described, a fastening conducting raceway, means for supporting the raceway comprising a member movable about an axis disposed substantially parallel to the plane of the fastenings conducted by the raceway, and means for adjusting the raceway relatively to the supporting means. 120

15. In a machine of the class described, a raceway, means for supporting the raceway comprising a member movable about an axis disposed substantially parallel to the vertical plane of the raceway, supporting members connected to the raceway at points 125 130

spaced longitudinally of the raceway, and means for adjusting one of said members relatively to said first-mentioned member.

16. In a machine of the class described, a raceway, a bracket for supporting the raceway movable about an axis transverse to the vertical plane of the raceway, and means for adjusting the raceway vertically relatively to the bracket.
- 10 17. In a machine of the class described, a raceway, supporting means for the raceway movable about an axis transverse to the vertical plane of the raceway, and connections between the raceway and the supporting means at spaced intervals longitudinally of the raceway, one of such connections comprising means for adjusting the raceway relatively to the supporting means.

18. In a machine of the class described, a raceway, supporting means for the raceway adjustable transversely of the plane of fastenings in the raceway, and connections between the supporting means and the raceway comprising means for adjusting the raceway relatively to the supporting means.

19. In a machine of the class described, a raceway, means for supporting the raceway, connections between the raceway and the supporting means comprising means for adjusting either end of the raceway relatively to the supporting means independently of the other, said supporting means being movable to effect bodily adjustment of the raceway.

20. In a machine of the class described, a raceway, and means for supporting the raceway comprising a plate having a stud projecting therefrom, a member pivotally mounted on the stud, a bracket mounted on said member for angular adjustment about an axis disposed substantially at right angles to said stud, and connections between the bracket and the raceway comprising means for adjusting the raceway relatively to the bracket.

21. In a machine of the class described, a raceway and a cover plate for the raceway movable about an axis disposed centrally of the cover plate and extending transversely of the vertical plane of the raceway, said axis constituting the sole support for the cover plate.

22. In a machine of the class described, a raceway, a cover plate for the raceway, supporting means for the cover plate movable about an axis disposed transversely of the raceway, and connections between the cover plate and its supporting means constructed and arranged to permit adjustment of the cover plate relatively to the supporting means.

23. In a machine of the class described, a bracket, a raceway, connections between the raceway and the bracket at spaced points

longitudinally of the raceway and comprising means for adjusting the raceway relatively to the bracket, and a cover plate adjustably carried by the bracket.

24. In a machine of the class described, a bracket, a raceway, connections between the raceway and the bracket at spaced points longitudinally of the raceway and comprising means for raising or lowering one of the ends of the raceway, and a cover plate fulcrumed on the bracket for movement in the vertical plane of the raceway.

25. In a machine of the class described, a bracket, a raceway, a cover plate for the raceway, connections between the raceway and the bracket at spaced points longitudinally of the raceway and comprising means for raising or lowering the raceway relatively to the cover plate, and supporting means for the cover plate constructed to permit vertical adjustment of the cover plate.

26. In a machine of the class described, a bracket, a raceway, a cover plate for the raceway mounted on the bracket, connections between the raceway and the bracket at spaced points longitudinally of the raceway and comprising means for raising or lowering the raceway relatively to the cover plate, supporting means for the cover plate constructed to permit adjustment of the cover plate independently of the raceway, and means for adjusting the bracket so as to adjust the raceway without changing the relation of the raceway and cover plate.

27. In a machine of the class described, a fastening receiving member having inwardly turned ends and a raceway, and members detachably connected to one of said parts for conducting fastenings from the raceway to the fastening receiving member.

28. In a machine of the class described, a driver guide, a raceway, and members detachably connected to the raceway for conducting fastenings from the raceway to the driver guide.

29. In a machine of the class described, a raceway constructed and arranged to support nails suspended by their heads and having removable tips at its delivery end.

30. In a machine of the class described, a fastening receiving member, a raceway, and removable tips on the delivery end of the raceway having their upper surfaces disposed substantially in alignment with the upper surfaces of the raceway and operable to conduct fastenings supported by their heads from the raceway to the fastening receiving member.

31. In a machine of the class described, a fastening receiving member, a slotted raceway, and means for guiding the fastenings from the raceway to the fastening receiving member comprising plates detachably connected to the raceway on opposite sides of

the raceway slot and having portions extending across the delivery end of the raceway substantially to the end of said slot.

32. In a machine of the class described a fastening receiving member, a slotted raceway, and means for conducting fastenings from the raceway to the fastening receiving member comprising plates detachably connected to the raceway on opposite sides of the raceway slot and having inwardly pro-

jecting portions extending across the delivery end of the raceway substantially to the end of said slot and having their upper surfaces disposed substantially in line with the upper surface of the raceway.

In testimony whereof we have signed our names to this specification.

GEORGE GODDU.
FRED L. MACKENZIE.

Certificate of Correction.

It is hereby certified that in Letters Patent No. 1,408,451, granted March 7, 1922, upon the application of George Goddu, of Winchester, and Fred L. Mackenzie, of Beverly, Massachusetts, for an improvement in "Nail-Feeding Mechanism," errors appear in the printed specification requiring correction as follows: Page 5, line 100, claim 27, after the word "member" insert a comma and the words, *a raceway, and members*, and lines 101 and 102, strike out the words "a raceway, and members"; and that the said Letters Patent should be read with these corrections therein that the same may conform to the record of the case in the Patent Office.

Signed and sealed this 12th day of September, A. D., 1922.

[SEAL.]

KARL FENNING,
Acting Commissioner of Patents.
